WHEEL TRUING BRAKE SHOE

Frederick W. MacDonald and Anthony Lavrino,
Detroit, Mich., assignors to Wheel Truing Brake
Shoe Company, Detroit, Mich., a corporation
of Michigan

Application October 31, 1949, Serial No. 124,647

2 Claims. (Cl. 51—204)

1

This invention relates to a new and useful device for truing wheels of railway vehicles.

Wheels of railway vehicles become deformed in a number of ways while the vehicles are in road service. The wheel flange may become too long due to excessive wear of the wheel tread, the tread may become flat in spots from skidding on the rail when the brakes have been applied, or the tread may be worn to a hollow or grooved shape. These conditions result in unsafe or poor riding conditions and must be corrected whenever they occur.

The present practice in the railway industry for correcting deformations in a railway wheel is either to remove the deformed wheel from the railway vehicle of which it is a part and perform the necessary cutting and grinding operations thereon, or to substitute for the conventional brake shoe of the deformed wheel a wheel truing brake shoe containing an abrasive material and to grind the wheel while the vehicle is in motion. Neither of these practices is in all instances satisfactory. In the former, the vehicles are rendered inoperative for excessive lengths of time causing economic losses, while in the latter, difficulty frequently is encountered in truing the wheel flange to its proper size with respect to the wheel tread.

The present invention overcomes these unsatisfactory practices and comprises a wheel truing brake shoe which can be used for truing wheels of railway vehicles while the vehicles are in road service by being substituted for the conventional brake shoe of a wheel which requires truing, or one which has a flange which must be cut down to size with respect to the wheel tread.

In the present invention a wheel truing brake shoe is provided which has a metal cutting tool for cutting the flange of the wheel combined with an abrasive material for grinding both the wheel tread and the flange.

It is a primary object of the present invention to provide, in combination, a cutting tool for cutting the flange portion of a wheel so as to restore the normal relationship between the wheel tread and the flange, and an abrasive element for further truing both the wheel tread and the flange of the wheel after the cutting tool has performed its function of trimming the flange.

It is another object of the invention to provide a novel wheel truing brake shoe for rapidly truing metallic wheel rims to a predetermined contour while the wheels are maintained in service.

It is another object of this invention to provide means for controlling the rate of feed of a cut-

2

ting tool for cutting the flange of a wheel and for maintaining substantially constant the difference in diameters of the flange and tread of said wheel.

Other objects of this invention will appear in the following description and appended claims, reference being had to the accompanying drawings forming a part of this specification wherein like reference characters designate corresponding parts in the several views.

In the drawings:

Fig. 1 is a plan view of the inner face of the wheel truing brake shoe.

Fig. 2 is an end view partly in section of the wheel truing brake shoe shown in Fig. 1.

Fig. 3 is a sectional view taken on the line 3—3 of Fig. 1.

Fig. 4 is a plan view of the modified form of the wheel truing brake shoe shown in Fig. 1.

Fig. 5 is a sectional view taken on the line 5—5 of Fig. 4.

Fig. 6 is a fragmentary perspective view of a railway wheel, partly in section, and a wheel truing brake shoe.

The preferred form of the present invention is illustrated in Figures 1—3, wherein a wheel truing brake shoe 10 is shown which has an arcuate shaped backing member 20 divided into a series of pockets 22 into which an abrasive material 24 is packed and fused by a heating operation. Spaces 26 are provided between the pockets 22, and a cutting tool 28 is held by the arcuate shaped backing member 20 at one side of the middle space 26. The tool is held in a suitable type of way 29 and is brazed or otherwise secured in position. The cutting edge 30 of the cutting tool 28 is formed to give a desired cut on the wheel flange of the wheel. An opening 32 in the arcuate shaped backing member 20 is provided through which chips cut by tool 28 will be thrown out of the shoe.

The abrasive material 24 is formed in two layers. A coarse abrasive 34 comprises the lower layer and has the primary function of truing the tread and flange of the wheel, and a fine abrasive 36, which is in the form of a pad disposed over the lower layer, has the primary function of controlling the rate of feed of the cutting tool 28 to the wheel flange. The thickness of the layer of fine abrasive 36 is predetermined so that the coarse abrasive 34 will commence to grind the wheel at about the time the flange has been cut by the cutting tool 28 to a desired size and shape with respect to the tread of the wheel.

Thus, two grades of abrasive materials are

utilized. One is a coarse grade for performing the major portion of the grinding operation. The other is a fine grade which is relatively soft and which wears more rapidly than the coarse abrasive. The fine abrasive is used as a pad over part or all of the coarse abrasive and is designed to wear away as the cutting tool cuts the flange while being supported and guided from the wheel tread by the said pad.

When the wheel truing brake shoe 10 is to be placed in operation, it is substituted for the brake shoe of the wheel requiring truing. The wheel truing brake shoe 10 is then applied to wheel 50, as shown in Fig. 6, while the vehicle is in operation in carrying out the truing operation. To permit interchangeability of these brake shoes a conventional brake shoe supporting means is employed with the present wheel truing brake shoe 10. As illustrated in the drawings, the arcuate shaped backing member 20 is provided on its outer side with a lug 38 for support thereof in a conventional brake shoe mounting means.

Fig. 4 and Fig. 5 illustrated a modified form of the invention shown in Figs. 1-3 and like parts are identified by like reference numbers.

In the modified form of the invention, cutting tool 40 is mounted at one end of the arcuate shaped backing member 20 rather than at the mid-portion as shown in the preferred form of the invention. The arcuate shaped backing member 42 is cut away, as at 44, so that the chips cut by the cutting tool 40 will fall out through the cut-away portion. This form of the invention is substantially the same in all other respects as the preferred form of the invention.

Each form of the invention has been found to be most suitable for certain operating conditions. In the form of the invention shown in Figs. 1-3, it has been found that greater support is provided for the cutting tool 28, since the arcuate shaped backing member 20 is supported adjacent the base of the cutting tool 28 at the lug 38, and there is less possibility of the cutting tool 28 being moved out of contact with the wheel flange when the brakes are applied than is the case with the form of the invention shown in Figs. 4 and 5. Because of the more rigid support for the cutting tool 28 provided in the preferred form of the invention, this form is found most suitable for use when it is desired to cut a flange having a rough outer edge or when a rapid feed of the cutting tool is desired. The modified form of the invention, which has the cutting tool 40 mounted away from the support for the arcuate shaped backing member 42, is found most suitable for use when it is desired to reduce gradually the

diameter of the wheel flange a relatively large amount.

Having thus described our invention, we claim:

1. A wheel truing brake shoe adapted for use in truing a conventional railway car wheel having a circumferential tread portion and a flange extending radially outwardly therefrom, said brake shoe comprising an arcuate shaped backing member having side and end flanges projecting inwardly from the concave surface thereof, a cutting tool holder in said backing member adjacent one of said side flanges and projecting inwardly from said concave surface, a cutting tool mounted in said tool holder and having a U-shaped cutting edge adapted for cutting the flange of said car wheel, and a coarse abrasive material mounted on the concave surface of said backing member between said side and end flanges and adapted for grinding the tread of said car wheel, said coarse abrasive material projecting inwardly further than said cutting tool so that the grinding and cutting operations can be carried out simultaneously on the tread and flange of said wheel.
2. The wheel truing brake shoe of claim 1 wherein the grinding surface of said coarse abrasive material projects inwardly of the cutting edge of said cutting tool a predetermined distance, and a relatively fine soft abrasive pad is mounted on the grinding surface of said coarse abrasive material so that when said brake shoe is initially applied to a railway car wheel having an abnormally long flange caused by wear of the wheel tread the rate at which said soft abrasive pad is worn away will control the rate of feed of said cutting tool.

FREDERICK W. MACDONALD.
